T. L. DUFFIELD

ROAD SCRAPER

Filed May 25, 1927

Inventor

Thos. L. Duffield

By *Herbert E. Smith*

Attorney

UNITED STATES PATENT OFFICE.

THOMAS L. DUFFIELD, OF ORIENT, WASHINGTON.

ROAD SCRAPER.

Application filed May 25, 1927. Serial No. 194,084.

My present invention relates to improvements in road scrapers or excavators of the drag type for general grading, leveling, smoothing and distributing the material on the road surface. Due to the simplicity of construction and minimum number of parts employed in the implement a strong, rugged and durable scraper is provided that may readily be repaired and in which parts may 10 with facility be replaced when required.

The implement involves essentially the use of a longitudinally disposed drag bar or beam and a transversely disposed scraper blade, with means for angularly adjusting 15 the scraper blade with relation to the beam in a horizontal plane, and with means for tilting the scraper blade. The scraper is thus adjustable for the purpose of laterally distributing the material of the road 20 surface and is adapted to be tilted for the purpose of performing the functions of a smoother so that the surplus or excess material may be smoothed down or deposited in the low places in the roadway.

The invention consists in certain novel 25 combinations and arrangements of parts as will hereinafter be more fully pointed out and claimed. In the accompanying drawings I have illustrated one complete example 30 of the physical embodiment of my invention wherein the parts are combined and arranged according to the best mode I have thus far devised for the practical application of the principles of my invention.

Figure 1 is a side view of an implement 35 embodying my invention, the scraper blade being shown in section.

Figure 2 is a top plan view of the implement with parts broken away for convenience of illustration.

Figure 3 is a front view of the drag beam showing the draft head, for hitching the power.

Figure 4 is a detail side view showing the 45 locking lever for the adjusting chain of the scraper blade.

Figure 5 is a rear end view of the drag beam.

In carrying out my invention I utilize a 50 longitudinally disposed drag beam 1 which is preferably made up of angle iron shapes, strong and rugged and of sufficient weight for the purpose. The driver occupies a seat 2 that is supported on the drag beam, at the 55 rear end of the implement, and horse-power or an automotive tractor may be utilized to

pull the implement along the road or over the surface to be graded. At the front of the drag beam is provided a hitching or coupling head 3 which is flanged and rigidly 60 attached to the beam and rises vertically therefrom to a suitable height. At its upper end the coupling head turns forwardly and its forked end is perforated to receive a king bolt or coupling pin 4 to pass through a 65 usual clevis or other attaching device on the draft device for the implement. At the rear of the beam, a shoe or skid 5 is provided, which projects below the lower edge of the beam and is designed to prevent lateral skid- 70 ding of the beam as well as to keep the implement moving along the desired draft line.

The scraper blade 6 is normally disposed transversely of the drag beam 1 at the front thereof and at its center is located under the coupling head, or its forwardly turned upper end. The blade is preferably a concavo-convex metal plate of convenient length and height and normally stands in vertical position, perpendicular to the road 80 surface. As indicated in Figure 2 the blade is capable of being turned to coincide with the dotted lines, and in these angular positions may distribute the material on the road surface laterally to the right or left. 85 The blade is also adapted to be tilted by swinging its upper edge to the front or to the rear thus presenting the lower edge of the blade in different positions for accomplishing various working conditions. 90

At the longitudinal center of the blade, near its lower edge and at its rear is provided a coupling head 7 rigidly attached to the beam and adapted to receive a coupling bolt 8 which co-acts with a clevis or yoke 9 95 which is pivoted at 9' to the draw head 3 of the longitudinal beam. By this coupling arrangement the blade may be swung horizontally with the bolt 8 as a pivot, or the blade may be tilted on the pivot 9' of the draw head, for accomplishing the above indicated adjustments.

A retaining chain is utilized in connection with the scraper blade for holding it in laterally adjusted position and this chain 13 100 is connected to the scraper blade near its ends by means of a pair of long links 10 and 11 each pivoted at 12 at the rear side of the scraper blade.

The chain passes to the rear from the 110 two links in angular formation and the peak of the angle of the chain is secured on the

drag beam 1. For this purpose I use a chain locking-lever 14 which extends longitudinally of the drag beam and is pivoted thereon at 15, at the front end of the lever, or the lever nearer to the scraper blade. As best seen in Figure 4 the lever is fashioned with a key-hole slot 16 which is adapted to permit passage therethrough of the links of the chain, and to lock the chain in adjusted position. The rear larger end of the slot permits the links to be pulled transversely through the lever, and freely, but the forward, narrow end of the slot is of proper size as to permit insertion and retention therein of one of the horizontally disposed links of the chain. With one horizontal link of the chain in this narrow slot, the two adjoining links, in vertical position, prevent transverse passage of the chain through the lever, and when the lever is turned back to position of Figure 1 the chain is locked in its desired adjusted position.

For locking the lever in position I use a U-shaped slide or keeper 17 that may be slid on and off the free end of the lever for locking or unlocking it, and when the lever has been unlocked it may be turned up to dotted position in Figure 4 to permit ready manipulation of the chain in adjusting it.

Means for tilting the scraper blade is readily accessible for the driver sitting in the seat 2, who may use the lever 18 that is pivoted on the drag beam at 19 and provided with a usual type of pawl 20 and rack segment 21.

Inasmuch as the scraper blade is fre-

quently adjusted or tilted during the operations of the implement for various distributions of the material on the road surface, the tilting may be accomplished with this manual control, and the manually operated lever 18 is connected to the scraper blade by a connecting rod 22 which is pivoted at 23 near the upper edge of the blade at its rear. The location of the pivotal connection of the rod at the upper edge of the blade provides for an efficient working leverage on the blade and by manipulating the lever 18 the blade may be tilted as desired on the pivot 9' as heretofore described.

Having thus fully described my invention, what I claim as new and desire to secure by Letters Patent is:

1. The combination with a drag beam 55 having a rear shoe and a front draw head, of a transversely disposed scraper blade having a coupling head at its rear center, a clevis pivoted to the coupling head and to the draw head whereby the blade may 60 be swung horizontally or tilted vertically means for holding the blade in adjusted horizontal position, and means for tilting and retaining the blade in tilted position.

2. The combination with a drag beam of 65 a scraper blade pivoted thereto and adapted to swing horizontally, a single retaining chain having end connections near the ends of the blade, and a locking lever having a key-hole slot pivoted on the drag beam, 70 said chain being passed through and locked in said lever as described.

In testimony whereof I affix my signature.
THOS. L. DUFFIELD.
